Primary Examiner — Deanna L Pratt*(74) Attorney, Agent, or Firm* — Brinks Gilson & Lione**(57) CLAIM**

The ornamental design for an arm for seating unit, as shown and described.

DESCRIPTION

FIG. 1 is a top front perspective view of a first embodiment of an arm for seating unit of the present design, shown with one environment;

FIG. 2 is a front-elevation view thereof;

FIG. 3 is a left side elevation view thereof;

FIG. 4 is a right side elevation view thereof;

FIG. 5 is a rear elevation view thereof;

FIG. 6 is a top plan view thereof;

FIG. 7 is a bottom plan view thereof; and,

FIG. 8 is a bottom front perspective view thereof.

Interior surfaces and other portions of the arm for seating unit not shown in the illustrated drawings, including the bottom, form no part of the claimed design. Uniform broken lines show environmental structure that forms no part of the claimed design, while the dash-dot-dash phantom lines of FIGS. 1-8 illustrate a symbolic break in the length of the arm for seating unit design, such that the portion between those phantom symbolic break lines forms no part of the claimed design.
